UNITED STATES PATENT OFFICE.

ORLAND V. SMITH, OF MILFORD, CONNECTICUT.

ACCOUNT DEPOSIT-BOOK.

1,101,346.

Specification of Letters Patent. Patented June 23, 1914.

Application filed January 22, 1914. Serial No. 813,710.

To all whom it may concern:

Be it known that I, ORLAND V. SMITH, a citizen of the United States, residing at Milford, in the county of New Haven and State of Connecticut, have invented certain new and useful Improvements in Account Deposit-Books, of which the following is a specification.

My present invention pertains to an improved account deposit book, the construction and advantages of which will be hereinafter set forth, reference being had to the annexed drawings, wherein:

Figure 1 is a perspective view of the book with the upper cover-board turned back, exposing to view the first sheet of the book, and the table upon the inner face of the board; Fig. 2 a similar view, the first leaf being turned up, exposing the second complete sheet; and Fig. 3 a like view, wherein two coupons have been removed from the book, stub No. 1 being turned up against the cover-board, leaving No. 2 in view, which latter, as will be seen, has been validated by the signature of the proper bank official.

The main object of the invention is to produce a book which will lend itself to the ready use of keeping track of a special account between a banking institution and a particular customer, so that the customer or depositor may know at all times the amounts which have been deposited and likewise such other amount or amounts as may be required to be deposited, from time to time, in order to fulfil the requirements of the contract entered into with the bank.

A further advantage arises from the fact that the system enables the bank to readily keep track of the account by the coupon system, which coupons are removed from the book, from time to time, as the money is paid by the customer.

A still further advantage arises from the employment of a table, so related to the stubs and coupons of the book, that the customer or the banking official may readily determine the amount necessary to be paid for any aggregate number of payment-periods, the corresponding number of stubs validated, and the companion coupons removed.

Of late there has come into vogue a special form of savings accounts commonly denominated "Christmas accounts" or "Christmas thrift clubs," under which a specified number of payments is made during the calendar

year, usually one a week, and at the end of the specified period the depositor is entitled to withdraw a fixed or determinate amount, commonly the amount paid in plus the agreed interest on such amount. The invention is illustrated in connection with such an account-book, though, of course, it is not limited thereto.

Referring to the drawings, 1 denotes the upper cover-board, having imprinted thereon a table, which in this instance is divided by suitable ruling into monthly spaces or periods, as, for example, December, 1913, January, 1914, and so on, to and including November, 1914, or a total of twelve months all told. Within each monthly space there appear the coupon numbers, as 1, 2, 3, for the month of December, with the date when the specific payment is due, followed by the specific amount payable on such date, and, in another column, the total amount for the month; as for instance, \$3.00, for the month of December. Headings appear at the top of the cover; above each column of numbers and dates, to clearly indicate the matter falling below the same. Preferably, the grand total to be paid and the date of closing the account, or when the total plus the interest becomes payable, also appear, all of which will be clearly seen upon an inspection of Fig. 1.

The book contains a series of leaves; fifty in all in the present instance, each leaf comprising a stub or stub coupon 2, and a detachable sheet or coupon 3, the parts being readily detachable on a weakened line 4 extending across the sheet. For the purpose of clearness in description, the portion 2 will hereinafter be denominated the "stub" and 3 the "coupon". Each stub and coupon throughout the book will preferably have thereon a class indication, as "Class B," and each will likewise bear an account number, as "Account No. 50028". The amount to be paid into the bank will likewise appear on each stub and coupon, as well as the serial number of each, the serial numbers running from 1 to 50 through the book. Said amounts and serial numbers will, of course, correspond to the like notations in the table above described.

The stubs will each be provided with a blank space, as 5, for the reception of the validating stamp or signature of the proper official, see Fig. 3, which is placed thereon at the time the payment is made, and the cor-

responding coupon is detached and retained by such official. This coupon takes the place of a deposit-slip, though, of course, an ordinary deposit-slip may be used in conjunction therewith and the coupon filed away, as under a card-index system, in order that the amount need not be entered in any special book or the like.

As above intimated, should a party desire 10 to pay, say, the amount for a month, in advance, he can readily determine the exact sum necessary to complete such payment by referring to the table hereinbefore mentioned, and can see, when the book is handed 15 back by the bank official, that the requisite number of coupons have been withdrawn and the corresponding stubs validated.

While, of course, the book may be employed without the table, such table is of 20 material benefit in making clear to the depositor exactly what is required at the given payment periods, and does away with any question as to the terms agreed upon between the bank and the special depositor.

25 Having thus described my invention, what I claim is:

1. A deposit book, adapted to indicate the amounts paid and to be paid by a depositor or a bank's customer, comprising a plurality 30 of sheets, each sheet consisting of a stub and a detachable coupon, the stubs and those coupons which remain attached to be held by the depositor until the account is closed, the stubs and coupons throughout the book bearing a common designating mark and being likewise serially numbered, and each stub having a space for the reception of a validating signature.

2. A deposit book adapted to indicate the 40 amounts paid and to be paid by a depositor or a bank's customer, comprising a plurality of sheets, each sheet consisting of a stub and a detachable coupon, the stub and those coupons which remain attached to be held by

the depositor until the account is closed, the 45 stubs and coupons throughout the book bearing an imprint indicating a specific money-value, each stub and coupon throughout the book likewise bearing a common designating mark and being serially numbered, and each 50 stub having a space left thereon for the reception of a validating signature, said signature being applied to each stub by a bank official as the corresponding coupon is detached and retained by said official as a bank 55 record.

3. A deposit book adapted to indicate the amounts paid and to be paid by a depositor or a bank's customer, comprising a plurality 60 of sheets, each sheet consisting of a stub and a detachable coupon, each stub and coupon bearing an imprint indicating a specific money-value, the stubs and coupons throughout the book bearing a common designating mark and likewise being serially numbered, 65 and the stubs having a space left thereon for the reception of a validating signature adapted to be applied by a bank official when the corresponding coupon is detached; and a table bearing serial numbers corresponding 70 to the serial numbers aforesaid and the amount of the money-value upon the serially-numbered sheets, said numbers and money-value designations being grouped into time periods, with the total money-value for each group separately expressed, the book containing the validated stubs and those coupons which remain attached to be held by the depositor until the full amount called for by the book has been deposited, 75 80 or the account closed.

In testimony whereof I have signed my name to this specification in the presence of two subscribing witnesses.

ORLAND V. SMITH.
